MARCUS A. FOOS, OF FREMONT, OHIO, ASSIGNOR TO NATIONAL CARBON COMPANY, OF CLEVELAND, OHIO, A CORPORATION OF NEW JERSEY.

DRY CELL

1,143,181.

Specification of Letters Patent. Patented June 15, 1915.

Application filed December 2, 1912. Serial No. 734,477.

To all whom it may concern:

Be it known that I, MARCUS A. Foos, a citizen of the United States, residing at Fremont, in the county of Sandusky and State of Ohio, have invented a certain new and useful Improvement in Dry Cells, of which the following is a full, clear, and exact description.

My invention relates to dry cells and one of the objects is to prevent the mix from falling between the lining and the container electrode.

Another object is to thoroughly insulate the top of the can to prevent short circuits between the two electrodes.

Other objects will appear in the appended description.

In the drawings: Figure 1 is a sectional view of a dry cell showing one way of constructing cells. Fig. 2 is a sectional view of a zinc container with my improvement applied, the thickness of each layer being somewhat exaggerated for the purpose of illustration. Fig. 3 is a partial sectional view of a modification.

Dry cells are constructed with bibulous linings between the zinc can or container to serve as a reservoir for the electrolyte and to prevent the mix from reaching the can. The mix must be thoroughly tamped in the cell in order to reduce the internal resistance and to make a solid, compact cell. In filling in the mix and the subsequent tamping, the particles are liable to fall between the lining and the container. This causes local action between the zinc and the particles, decreasing the life and utility of the cell. The mix is also liable to extend above the lining and cause a short circuit between the central electrode and the container electrode. To prevent both of these difficulties the lining 1 of the cell was made long enough to extend above the container 2 and turned over as at 3 so that the mix could be filled in and

tamped with minimum chance of the particles falling between the lining and the container. After the mix was thoroughly tamped around the electrode 4 the upper part of the lining was turned over the top of it as at 5. In bending the lining over the mix it is liable to become broken or torn, allowing the mix to reach the container. To avoid these difficulties I have devised schemes as shown in Figs. 2 and 3.

Referring to Fig. 2, the container is provided at the top with an internal coat 6 of pitch, asphaltum or analogous insulating material which would ordinarily extend down about 14 inches from the top. The coat may be applied with a brush or the can may be inverted and dipped into hot material the proper depth. The latter process would also coat the outer part of the can, but this is immaterial. Other ways for applying the coat may be used. After the coat is applied the lining 1 and bottom 6' are placed in the can. The lining is made shorter than the can as shown, but extends above the lower edge of the coating. The second coat 7 of pitch or analogous insulating material is applied on top of the first coat and overlies the upper edge of the lining. The can is then ready to be filled and tamped and sealed in the usual way. The two coats inclose the upper end of the lining, and effectually prevent the mix from reaching the container electrode during the subsequent steps taken to complete the cell. The top of the lining is, of course, not turned over the mix as in the old types.

In Fig. 2 the second coat 7 is shown as overlapping the end of the lining, but this may not always be necessary. In Fig. 3 the coat 7 is shown as abutting against the end of the lining and not extending over it. This would prevent the mix from reaching the container if it were applied carefully so as to leave no crevice between the lining and the coat. The lining is also liable to be moved downward in the tamping process and for these reasons it is preferable to apply the coat so that it extends past the end of the lining, particularly if the lining has been previously wetted.

It is preferable to apply two coats to the cell as described, but it is not absolutely necessary. In some cases the coat 6 may be dispensed with.

My invention therefore provides means for effectually preventing the mix from reaching the zinc can and eliminates the troubles caused by such defects in prior cells.

Having described my invention what I claim is:

1. In a dry cell, a container adapted to receive a mix, a bibulous lining therein and an adherent guard applied to the container and extending over the end of the lining to

prevent the mix from reaching the container, while it is being placed therein.

2. In a dry cell, a container adapted to receive a mix, a bibulous lining therein and a 5 guard closely fitting the end of the lining to prevent the mix from reaching the container while it is being placed in the cell.

3. In a dry cell, a container closed at one 10 end adapted to receive a mix, an insulating coating on the inside of the container at the open end, a bibulous lining overlapping the coating and a second coating overlapping the lining.

4. In a dry cell, a container closed at one 15 end adapted to receive a mix, a coating of pitch on the inside of the container at the open end, a bibulous lining overlapping the coating and a second coating of pitch overlapping the lining.

20 5. The steps in the process of making dry cells which consist in placing the bibulous lining in the container, applying an adherent insulating coating on the inside of

one end of the container and lining, and filling the mix therein.

25 6. The process of making dry cells which consists in placing the bibulous lining within a container, applying an adherent insulating coating to the interior of the container and lining at the open end, and filling 30 the mix therein.

7. The process of making dry cells which consists in placing a bibulous lining within a container, dipping the open end of the container in a molten carbonaceous material 35 to coat the interior of the lining and container for the short distance from the top, allowing the coating to congeal, and filling the mix in the receptacle thus formed.

In testimony whereof, I hereunto affix my 40 signature.

MARCUS A. FOOS.
